(57) **CLAIM**

The ornamental design for a pad with protective panel, as shown and described.

DESCRIPTION

FIG. 1 is a perspective view of a pad with protective panel showing my new design;

FIG. 2 is an enlarged view of the encircled portion identified as "2" in FIG. 1;

FIG. 3 is an enlarged view of the encircled portion identified as "3" in FIG. 1;

FIG. 4 is a front plan view of the pad with protective panel of FIG. 1, the rear view thereof being identical;

FIG. 5 is a left side elevational view thereof;

FIG. 6 is a right side elevational view thereof;

FIG. 7 is a bottom view thereof, the top view thereof being a mirror image;

FIG. 8 is an enlarged view thereof of the encircled portion identified as "8" in FIG. 7;

FIG. 9 is an enlarged view thereof of the encircled portion identified as "9" in FIG. 7;

FIG. 10 is a rear view of the pad with protective panel of FIG. 1;

FIG. 11 is a perspective view of the pad with protective panel of FIG. 1 shown in an alternate position;

FIG. 12 is a perspective view of the pad with protective panel of FIG. 1 shown in an alternate position;

FIG. 13 is a perspective view of the pad with protective panel of FIG. 1 shown in an alternate position;

FIG. 14 is a perspective view of the pad with protective panel of FIG. 1 shown in an alternate position; and,

FIG. 15 is a perspective view of the pad with protective panel of FIG. 1 shown in an alternate position.

The evenly spaced broken lines immediately adjacent to the claim represent the bounds of the claimed design, while all other evenly spaced broken lines encircling portions of the claimed design in FIGS. 1 and 7 that are illustrated enlargements in FIGS. 2, 3, 8, and 9 form no part of the claimed design.

(Continued)

The densely spaced occasionally broken lines shown on the bottom and right side edges indicate a contrast in appearance as shown.
